[57] CLAIM

The ornamental design for a video cassette recorder, as shown and described.

DESCRIPTION

FIG. 1 is a perspective view from the front, top and right side of a video cassette recorder showing our new design;

FIG. 2 is a top plan view thereof;

FIG. 3 is a front view thereof;

FIG. 4 is a bottom plan view thereof;

FIG. 5 is a rear view thereof;

FIG. 6 is a right side elevational view thereof (a left side elevational view is a mirror image of the right side view);

FIG. 7 is a perspective view from the front, top and right side thereof shown in use; and,

FIG. 8 is a perspective view from the rear, top and left side thereof.
